UNITED STATES PATENT OFFICE.

FRANKLIN A. PIERCE AND BENJAMIN W. DAVIDSON, OF STEUBENVILLE, OHIO,
ASSIGNORS OF ONE-FIFTH TO JOHN G. MINKEMYER, ONE-FIFTH TO JAMES B.
MINKEMYER, AND ONE-FIFTH TO E. M. BONNELL, ALL OF WHEELING, WEST
VIRGINIA.

DROP FENDER FOR VEHICLES.

Application filed June 17, 1922. Serial No. 569,011.

To all whom it may concern:

Be it known that we, FRANKLIN A. PIERCE and BENJAMIN W. DAVIDSON, citizens of the United States of America, and residents of 5 Steubenville, county of Jefferson and State of Ohio, have invented certain new and useful Improvements in Drop Fenders for Vehicles, of which the following is a specification.

10 This invention relates to drop fenders for motor vehicles, and it has for its principal object to provide a simple, efficient and improved construction of fender, designed primarily for use on automobiles and motor 15 trucks, which is adapted through forcible engagement with a person in the roadway to be instantly tripped, or actuated to drop, to a lowered position and upon which such person may fall and be carried with minimum 20 danger of serious injury.

With this and other important objects in view, the invention resides in the features of construction, arrangement of parts and combinations of elements which will herein- 25 after be fully described, reference being herein had to the accompanying drawings, in which—

Figure 1 is a top plan view of the invention applied to an automobile;

30 Figure 2 is a front elevation of the same; and—

Figure 3 is a section on line 3—3, Fig. 2.

Referring to said drawings, 1 indicates each of two upright hollow cylindrical casings which are carried by supporting brackets 2 mounted upon the front ends of the opposite sides 3 of the frame of the automobile. Extending upward into said casings through central openings 4 provided in the 35 lower ends of said casings are upright arms or members 5 which have their lower ends disposed in rigid supporting relation to a fender which comprises a horizontally disposed carrying portion, designated generally by the numeral 6, and a plurality of upright guard portions 7, 8 and 9. Said carrying portion 6 consists of a suitable lattice work or wire netting 6^a carried by a substantially rectangular frame 6^b, and each of said guard 40 portions consists of a lattice work or netting carried by a frame of substantially U-shape, inverted, having its ends mounted upon the

rear transverse member of the frame of the carrying portion 6. The guard portion 8 occupies practically the entire width of the 55 space between the casings 1, while the portions 7 and 9 are disposed laterally with respect to said casings, as shown.

The upright arms 5 and the various frames of the carrying and guard portions 60 are preferably made of metal tubing, and the frames of said guard portions, as also the lower ends of the supporting arms 5, are preferably welded to the rear member of the frame of the carrying portion 6, thus providing a perfectly rigid non-rattling fender structure.

Each of the supporting arms 5 has a notch 10 formed in the front face thereof adjacent to its lower end, said notch being adapted 70 for the reception of a rearwardly directed tongue or lug 11 formed on the lower closed end of the casing 1, whereby the fender structure described is normally supported in an elevated position. A spiral compression 75 spring 12 encircles each arm 5, being interposed between a fixed collar 13 carried by the arm and an adjustable hollow plug which is threaded within the upper end of the casing. When the fender is shifted rearward to a point at which the lugs 11 are disengaged from the notches 10 of the supporting arms 5, thus releasing said arms, the 80 previously compressed springs 12 instantly expand and thrust said arms downward to 85 positions in which the collars 13 thereof seat upon the lower ends of said casings, thus lowering the fender to a position in which the carrying portion 6 occupies a level closely adjacent to the roadway, as shown in 90 dotted lines in Fig. 3.

The release of the arms 5 may be effected automatically through forcible contact of the fender with an object or person in the roadway, or it may be manually effected 95 from the driver's seat by a pull applied through a cable, as 15, attached to the fender and passed about one or more suitably located pulleys, as 16.

The casing opening 4 through which each 100 supporting arm 5 extends is obviously of sufficient size to allow movement of the arm therethrough past the supporting lug 11. Suitable means is provided for preventing

chance disengagement of the arm 5 from said lug, the means herein shown comprising a coil spring 17 disposed in yieldable pressure-exerting relation to a stem 18 which carries a roller 19 seated against the rear face of the arm 5 adjacent to the lower end of the latter. Said stem projects outward through the front end of a small casing 20 which houses said spring 17, as shown. Said casing 20 is suitably mounted upon an adjacent portion of the automobile frame 3. As is obvious, the elevated fender is shifted rearward to an unsupported position against the tension of said spring 17.

15 A cap 21 is preferably carried by the upper end of each casing 1, as shown.

What is claimed is—

1. A drop fender for motor vehicles, comprising a pair of upright stationary casings located at opposite sides of the front end of the vehicle, upright arms extending into said casings, a fender frame carried in fixed relation to and supported by said arms, said arms having recesses therein and said casings having rearwardly directed lugs interengageable with said recesses for supporting said arms in elevated position, said lugs being adapted to be disengaged through rearward shifting of said frame for releasing said arms, and a spring-pressed roller resisting such shifting.

2. A drop fender for motor vehicles, comprising a pair of upright stationary casings located at opposite sides of the front end of the vehicle, arms extending into said casings through the lower ends of the latter, a fender frame supported by said arms, a collar carried by each arm, a compression spring encircling each arm and seated on the 40 collar thereof, a plug adjustable in the upper end of each casing whereby the tension of said spring may be regulated, interengageable means borne by said casings and said arms whereby the latter are supported in elevated position against the tension of said springs, said means being adapted for disengagement through rearward shifting movement of said frame for allowing said arms to drop, and means normally resisting such shifting movement, said collar being adapt-

ed when said arms are dropped to seat for supporting the latter in lowered position.

3. A drop fender for motor vehicles, comprising a fender frame having upright supporting members, said frame and said members being composed of rigidly related tubing sections, casings having said members vertically movable with respect thereto, a lug formed on each casing, said members having notches therein for receiving said lugs whereby said members are supported in elevated position, said lugs being adapted to be disengaged from said notches by rearward shifting movement of said fender frame, springs whereby the released members are thrust downward, a spring pressed roller disposed rearward of each of said supporting members and yieldingly resisting rearward shifting, and means limiting the extent of lowering movement of said fender frame.

4. A drop fender for motor vehicles, comprising a fender frame having upright supporting members, casings having apertured lowered ends and having said members vertically movable through the apertures of said ends, interengaging means whereby said members are supported in elevated position, said means being adapted to be disengaged by rearward shifting movement of said fender frame for allowing said members to drop, a spring-pressed roller bearing against the rear face of each of said members and yieldingly resisting such shifting movement, compression means located within said casing whereby said members are instantly thrust downward following disengagement of said supporting means, and collars carried by said members and adapted to seat upon said lower ends of the casings for limiting the extent of downward movement of said supporting members.

In testimony whereof we affix our signatures in presence of two witnesses.

FRANKLIN A. PIERCE.
BENJAMIN W. DAVIDSON.
